RAILWAY CAR MOVER

William H. F. Miehe, Redwood City, Calif.

Application February 6, 1951, Serial No. 209,585

4 Claims. (Cl. 254—38)

1

This invention relates to new and useful improvements in railway car mover. More particularly, the invention constitutes an improvement on my patent, No. 1,994,530, issued March 19, 1935, for Power Car Mover.

One of the important features of the invention is the fact that the effective stroke of the shoe which delivers the power to the railway car wheel may be adjusted, thereby providing the desired power suitable for the load condition of the car being moved.

Another feature of the invention is the provision of means whereby said shoe is so connected to the mechanism transmitting power to said shoe that it may adapt itself to the contour of the wheel being moved, thereby avoiding point contact which might result in damage, and affording the advantage of full contact of the shoe with the surface being moved.

Still another feature of this invention is the fact that means is provided for raising the wheels attached to the car mover so that the device may be readily transported from one location to the other.

Another advantage of the instant invention is the fact that it may readily be adapted for use as a jack, in that a substantially vertical power stroke is provided and the operator may insert shims under the object being raised after each stroke. The device may thus be employed as a

loading platforms and the like. The device operates by imparting a relatively short, substantially vertically upward stroke to the underside of a railway car wheel, thereby rolling the same. 5 Accordingly, in the accompanying drawings reference numeral 10 represents a standard railway car wheel on a standard rail 11. The instant device is contained in and about a casing 12 having a flat undersurface 13 which sets upon the 10 rail head. A portion of casing 12, indicated by reference numeral 14, is arcuate in contour, having the same radius of curvature as wheel 10. As shown, particularly in Fig. 1, the device thereby is shaped so as to fit under the rear of a wheel 15 to move between the wheel and the rail. A serrated block 16 is fixed to the underside of the surface 13, the function of said block being to grip rail 11 so that as force is imparted to wheel 10, casing 12 is stationary and the car is pushed forward rather than the mover being pushed rearwardly.

An upwardly and rearwardly extending handle 17 is attached to casing 12, said handle being of a height so that it may be used conveniently by 25 the operator to control the car mover. A reel 18 is rotatably fixed to said handle, said reel functioning to contain and wind an electric cord 23 which furnishes electric power for the operation of motor 19 attached to casing 12. A switch 21 is attached to handle 17 so that the electric current may be turned off and on. It will be understood that electric plug 22 is connected to a convenient outlet box and that the electric cord 23 is unwound as the device is moved. Upon disconnection of the plug 22 from said outlet box, cord 23 is wound within reel 18 by action of a spring (not shown).

In order to transport the device from one location to another, a pair of wheels 26 is provided on either side of the device. Said wheels are mounted on spindles 27 which are journaled in rearwardly extending yokes 28. Said yokes 28 are fixed for rotation with transverse shaft 29 and to said shaft is fixed one end of lever 31, the 40 opposite end of which is pivotally connected to the lower end of link 33 extending upwardly generally parallel to handle 17. The upper end of link 33 is in turn pivotally connected to wheel control lever 36 intermediate to ends thereof. 45 The inner end of lever 34 is pivotally connected to handle 17 and the opposite end is provided with a hand grip 36. Thus, as shown particularly in Fig. 1, wheels 26 may be elevated so that the casing surface 13 and block 16 engage rail 11. When 50 it is desired to move the device to a new loca-

In the drawings:

Fig. 1 is a side elevation of the device as used to move a standard car wheel along a rail.

Fig. 2 is a top plan partially broken away in section.

Fig. 3 is a vertical section taken substantially along the line 3—3 of Fig. 2.

Fig. 4 is a vertical section taken substantially along the line 4—4 of Fig. 2.

The instant invention is a convenient, portable device for moving railway cars along rails in order to position said cars adjacent convenient

tion, the operator pulls grip 36 upwardly to the dotted position shown in Fig. 1 thereby pulling link 33 upward, pivoting link 31 upwardly causing rotation of shaft 29 thereby depressing yokes 28 to the dotted position shown in Fig. 1 and simultaneously lowering wheels 26 to said position. It will thus be seen that the operator may then push or pull the device to any location by moving handle 17.

The propulsive force is imparted to said wheel 10 by shoe 41, said shoe being caused to move against the undersurface of said wheel 10 through an opening 42 in casing 12. The surface of shoe 41 engaging wheel 10 is arcuate in configuration, having the same radius of curvature as wheel 10 and thus being engageable with the wheel 10 over a wide surface area. Further to improve the contact between shoe 41 and wheel 10, a flexible mounting is established between said shoe 41 and lever 43 which moves said shoe. Said flexible mounting is maintained by reason of the fact that the anterior end of lever 43 is formed in a ball 44 which fits into a semi-spheroidal socket 46 on the inner side of shoe 41. Screw 47 connects shoe 41 to ball 44, said screw 47 being received in a tapped hole in ball 44. In order to permit movement of shoe 41 relative to lever 43, the hole 48 in shoe 41 through which screw 47 passes is machined large so as to permit sufficient movement of shoe 41 relative to screw 47 so that shoe 41 may adjust itself to the configuration of wheel 10 or other object being moved. It will be seen particularly with reference to Figs. 3 and 4 that shoe 41 may adjust itself freely within the limits of the excess diameter of hole 48 without impairing the movement imparted to shoe 41 by lever 43.

As shown particularly in Figs. 3 and 4 lever 43 receives a rocking movement. Thus an arcuate fulcrum 51 is formed in lever 43 adjacent ball 44 and said fulcrum 51 is received in cradle bearing 52 mounted in casing 12. Said cradle bearing 52, which is concave and of a spheroidal segment configuration is held in place by screws 53 so that bearing 52 may be replaced when worn. It will be seen that the projection of the line of force from shoe 41 passing through bearing 42 intersects block 16 and thus as force is transmitted to wheel 10, a reaction force is imparted to block 16, the serrations of which tend to dig into the surface of rail 11 and hold the device in place.

The end of lever 43 remote from fulcrum 44 is caused to rock about said cradle bearing 52 by reason of force transmitted thereto from motor 19 through gearing and linkages hereinafter described. In Fig. 3 shoe 41 is shown retracted within casing 12, or, in other words, shoe 41 is at the inner end of its stroke. In Fig. 4 shoe 41 is shown projected through the opening 42 in casing 12 at the outer end of its stroke. The difference in position of lever 43 at the two positions of its stroke is thus emphasized by said Figs. 3 and 4.

One means whereby the end 54 of lever 43 is caused to rock will next be described, it being understood that any proper gearing, crankshaft, and connecting rod arrangement may be employed. Motor shaft 56 is received within bearings 57 and 58 in casing 12 and said shaft 56 is provided with a worm 59 meshing with worm wheel 61 mounted on worm wheel shaft 62 extending transversely through and journaled within casing 12. The end of shaft 62 opposite worm wheel 61 is provided with a pinion 63 which in

turn meshes with spur gear 64 mounted on transverse shafts 66, said shafts 66 likewise being journaled within casing 12. To shafts 66 is keyed a pair of crank links 67 which act in the nature of a crank. Extending between links 67 is a pin 68 horizontally and transversely disposed. Said pin 68 is received in connecting rod 69, said connecting rod 69 being formed with a cap 71 held in position about pin 68 by screws 72. The opposite end of connecting rod 69 is bifurcated, as indicated by reference numeral 73, and between bifurcations 73 is received the reduced upper end 54 of lever 43. Pin 74 passes through end 54 and bifurcations 73, linking the same together. It will be understood that suitable bushings or sleeves are interposed between shaft 66, pin 68 and pin 74 and the respective links receiving same.

As electric motor 19 revolves, worm 59 is likewise caused to revolve, which turns worm wheel 61, pinion 63 and spur gear 64. The gear ratios are such that a considerable speed reduction is effected by reason of the fact that the driving gears are smaller than the driven gears. Gear 64 causes shaft 66 to revolve, which motion is transmitted through crank link 67 to pin 68 and said motion is in turn transmitted through connecting rod 69 to pin 74 fixed to lever 43. As shown particularly in Figs. 3 and 4 as shaft 66 revolves, lever 43 is rocked about cradle 52 as a fulcrum as has been heretofore described.

Provision is also made for adjustment of the stroke of shoe 41. Thus at the toe of casing 12 an opening 81, is provided, said opening receiving ball or roller 82 on the outer end of rod 83. Rod 83 may be caused to project or retract by mechanism hereinafter described. In its retracted position ball 82 merges with the curvature of arcuate surface 14 as shown in Fig. 3 and in its projected position ball 82 projects above said surface 14 as shown in Fig. 4. Projection of pin 83, which is received and journaled within casing 16, and extends out through the back of said casing 16, is accomplished by movement of bell crank lever 91 attached to the rearward end of rod 83. The intermediate portion of bell crank lever 91 is pivotally mounted on casing 12 and the opposite end is pivotally connected to link 92 extending up handle 17, the upper end of link 92 being pivotally connected to handle 93 mounted on said handle 17 and adjustably held in a plurality of positions by a spring pressed detent (not shown) engageable with notches in arcuate rack 94 on said handle 17.

In order to move ball 82 from the retracted position shown in Fig. 3 to the protracted position shown in Fig. 4, the operator pulls handle 93 upward and said motion is transmitted by means of the linkages herebefore described in such manner as to project ball 82. Similarly, to retract ball 82, handle 93 is moved from the upper position shown in Fig. 1 in a counter-clockwise direction, which said motion is transmitted to said linkages to retract rod 83. It will be understood that handle 93 may be adjusted in a plurality of positions by means of rack 94, thereby fixing ball 82 in a corresponding plurality of positions. When ball 82 is projected, shoe 41 performs no effective work on wheel 10 for the initial portion of its outward stroke. Thus a shorter effective stroke of shoe 41 is provided, and more power is transmitted to shoe 41 although the stroke is the same. Thus, assuming that a car to be moved is fully loaded, ball 82 is projected to nearly the outer extremity of its

movement, thereby getting maximum power and lesser speed. After the inertia of the car has been overcome, the operator may readjust handle 93 so as partially to retract ball 82 and increase the speed of movement of the car. On the other hand, if the car is empty, ball 82 may be at least partially retracted at the commencement of operation.

Operation

In order to transport the device to the car to be moved, hand grip 36 is elevated to the position shown in Fig. 1 in dotted lines, and this causes wheels 26 to be lowered. Electric plug 22 is connected to a convenient outlet box and thereupon electric cord 23 is unwound from reel 18 as may be required. The operator then depresses hand grip 36 to the full line position shown in Fig. 1, thereby elevating wheels 26 and causing the undersurface 13 and particularly the serrated block 16 to engage rail 11 on which the wheel 10 of the car rests. The device is pushed under the wheel 10 as far as possible as shown in Fig. 1. The operator adjusts handle 93 depending upon the load condition of the car—i. e., if the car is heavy, ball 82 is projected and if the car is light, said ball is partially retracted. Switch 21 is turned on which causes motor 19 to operate. Electric motor 19 causes shoe 41 to push against the underside of the car wheel as lever 43 is caused to rock about cradle 52. The operator pushes against handle 17 to keep the device in contact with wheel 10 and hence as shoe 41 reciprocates through opening 42 strokes are imparted to wheel 10 causing the same to revolve in a counter-clockwise direction as viewed in Fig. 1. As the inertia of the car is overcome handle 93 may be adjusted for longer effective strokes by retracting ball 82. The device is thus pushed along, following the car as it moves down the track to the desired location. When the desired location is reached, switch 21 is turned off, the plug 22 is disconnected from the outlet box and the electric cord 23 rewound on reel 18. Hand grip 36 is raised to the position shown in Fig. 1 in dotted lines, thereby lowering wheels 26 and enabling the operator to move the device to another location.

It will further be seen that the apparatus may be used as a jack by causing shoe 41 to elevate the object to be raised and inserting shims under the object between strokes of shoe 41.

Although I have described my invention in some detail by way of illustration and example for purposes of clarity of understanding, it is understood that certain changes and modifications may be made therein without departing from the spirit of the invention or scope of the appended claims.

I claim:

1. A car mover comprising a casing having a rail-engaging surface and an arcuate surface conforming to the curvature of a car wheel, said arcuate surface having a first aperture, a shoe shaped to engage a car wheel, said shoe being projectable through said first aperture, a rocking lever mounted in said casing, a spheroidal-convex fulcrum formed on said rocking lever intermediate the ends thereof, a spheroidal-concave cradle bearing receiving said fulcrum, said cradle bearing being fixed in said casing, the end of said rocking lever having a spherically shaped bearing surface adjacent said shoe, said shoe having a concave socket complementary to said end and receiving said end, said shoe being apertured

in a direction normal to said spherical end, a screw fastener passing through the aperture in said shoe and being retained by said lever, the diameter of said screw being less than that of said aperture to permit said shoe to conform to the configuration of said car wheel, a prime mover, and means articulately connecting said prime mover to the end of said rocking lever opposite said spherical end to rock said rocking lever about said cradle bearing as a fulcrum and project and retract said shoe in a direction substantially normal to said arcuate surface.

2. A car mover comprising a casing having a flat, bottom, rail-engaging surface and an arcuate surface having two openings, a shoe projectable through one opening in said arcuate surface, means for imparting motion to said shoe to project and retract said shoe in strokes of equal amplitude, a protuberance projectable through the second opening in said arcuate surface, said protuberance being positioned and arranged to limit the minimum proximity of said second surface to the wheel to be moved, and means on said car mover for manually adjusting the length of projection of said protuberance to a fixed distance of projection relative to said casing and holding the protuberance in such position, said protuberance being fixed in position once adjusted until further adjustment thereof is made manually, said protuberance when adjusted regulating the effective length of stroke of said shoe and the ratio of power to the amplitude of stroke.

3. A car mover comprising a casing having a flat, bottom, rail-engaging surface and a second surface having two openings, a shoe projectable through one opening in said second surface, means for imparting motion to said shoe to project and retract said shoe in strokes of equal amplitude, a protuberance projectable through the second opening in said second surface, said protuberance being positioned and arranged to limit the minimum proximity of said second surface to the wheel to be moved, and means on said car mover for manually adjusting the length of projection of said protuberance to a fixed distance of projection relative to said casing and holding the protuberance in such position, said protuberance being fixed in position once adjusted until further adjustment thereof is made manually, said protuberance when adjusted regulating the effective length of stroke to said shoe and the ratio of power to the amplitude of stroke.

4. A car mover comprising a casing having a rail-engaging surface and an arcuate surface conforming to the curvature of a car wheel, said arcuate surface having a first aperture, a shoe shaped to engage a car wheel, said shoe being projectable through said first aperture, a rocking lever mounted in said casing, a spheroidal-convex fulcrum formed on said rocking lever intermediate the ends thereof, a spheroidal-concave cradle bearing receiving said fulcrum, said cradle bearing being fixed in said casing, the end of said rocking lever having a spherically shaped bearing surface adjacent said shoe, said shoe having a concave socket complementary to said end and receiving said end, said shoe being apertured in a direction normal to said spherical end, a screw fastener passing through the aperture in said shoe and being retained by said lever, the diameter of said screw being less than that of said aperture to permit said shoe to conform to the configuration of said car wheel, a prime

mover, means articulately connecting said prime mover to the end of said rocking lever opposite said spherical end to rock said rocking lever about said cradle bearing as a fulcrum and project and retract said shoe in a direction substantially normal to said arcuate surface, said arcuate surface having a second aperture, a protuberance horizontally projectable through said second aperture in said arcuate surface, and means on said car mover manually operable to adjust the length 10 of projection of said protuberance to a fixed distance of projection relative to said casing and hold the protuberance in such position, said protuberance being fixed to position once adjusted until further adjustment thereof is made manu- 15

ally, said protuberance when adjusted regulating the effective length of stroke of said shoe and the ratio of power to amplitude of stroke.
